GOLF CLUB

William James Hadden, Glasgow, Scotland, assignor to Donaldson Manufacturing Company Limited, Glasgow, Scotland

Application December 9, 1929, Serial No. 412,584
In Great Britain September 3, 1929

8 Claims. (Cl. 273—80)

This invention relates to metallic shafted golf clubs, such as drivers, brassies, etc., having wood heads.

Steel shafts are now used extensively for golf clubs and in some cases are adapted to be easily removed from or attached to heads (usually of metal), by screw means, in order to enable a number of suitable shafts and heads to be tried before the desired style and balance of club is obtained.

Several disadvantages have to be coped with in the attachment of steel shafts to wooden heads by screwing the two parts together; such as, lack of positive grip between the wood head and steel shaft, tendency of the relatively soft wooden parts contacting with the steel parts to give more or less when in use, and so render the club unsatisfactory, and lack of strength in the socket part of the wooden head.

20 The object of the present invention is to overcome the above disadvantages, by providing a metal to metal joint between the wood head and the steel or other metallic shaft. A further object is to provide such a joint which will secure the 25 shaft and wood head tightly together, while permitting them to be separated easily when required.

A still further object is to provide a device or tool for inserting a metallic liner in a wood head for a golf club.

30 A golf club according to the present invention, may comprise, in combination, a shanked wooden head, an internally tapered and partly screw threaded socket in said shank, a tapered and screw threaded metallic liner in said socket, and a tapered metallic shaft screw threaded at its lower end in order to form a combined screw joint and tapered push joint with the interior of said lined socket.

A special tool is provided for inserting the liner 40 in the club head.

I will now describe, by way of example, one mode of carrying out my present invention, with reference to the accompanying drawing, whereon:—

45 Fig. 1 is a sectional view through a wooden head for a "driver" golf club.

Fig. 2 is an elevation of a metallic tapered and partly screw threaded liner for the socket of the said head.

50 Fig. 3 is an elevation of a tool for use in screwing the liner into place in the socket.

Fig. 4 is a view showing the liner in section, with the tool screwed into it.

Fig. 5 is a sectional view showing the liner and 55 a tubular steel shaft screwed home and secured in the head.

Referring to the drawing:—

The wooden golf club head 6 has a shank 7 provided with an internally tapering socket 8 comprising a plain tapering portion 8a and a screw

threaded cylindrical portion 8b. The socket is tapered so that it converges, from its upper end towards the sole 9 of the head.

The metallic liner 10 (see Fig. 2) has a plain tapering portion 10a and a screw threaded cylindrical portion 10b, and the tapering portion converges in the direction of the end at which the threaded portion is located.

Preferably the threaded portion of the liner is formed by bending the metal thereof into screw formation; this may be done by introducing a helically grooved device into the liner, acting on the part of the liner to be threaded, by a tool which forces the metal by bending action into the helical groove on said device, and relatively rotating the liner and grooved device and the tool.

The threaded and tapered portions of the socket and liner are made to correspond. The external thread on the liner is adapted to engage with the internally threaded portion 8a of the socket 8, 20 and said external thread on the liner also forms on its reverse side the internal thread for the reception of a threaded portion on the metallic shaft of the golf club. The thread on the shaft may be formed in similar manner to that on the liner.

In order quickly and easily to screw the liner into the socket, the tool shown in Fig. 3 is provided. This tool consists of a handle 11 and a tapered shank 12, which is of circular cross section and has a portion 12a of reduced diameter and a cylindrical screw threaded portion 12b which itself has a portion 12c of reduced diameter. When the tool is screwed into the liner, the relative motion of the screwed portions 12b, 10b draws the tapered portions 10a and 12 into interengagement and binds the tool and liner frictionally together, making a combined screw joint and tapered push joint; this enables the liner to be screwed into the socket by means of the handle 30 on the tool. To remove the tool it is simply unscrewed a few turns and then withdrawn; the portion 12a of reduced diameter helps in giving a quick release. The portion 12c of reduced diameter compensates for slight errors in the sizes 35 of the tool or liner, ensuring that the screw threaded limit of the portion 12b of the tool will not be reached before the tapered portions 10a and 12 come into interengagement.

The joint between the liner and the socket may 50 be strengthened by the addition of glue, varnish or the like and instead of, or in addition to, this, a pin, nail, screw or other device may be passed through the liner into the wooden part of the head or socket in order to lock the liner positively therein, as illustrated by the nail 13 (Fig. 5).

To enable the tubular steel shaft 14 to be attached to the head, the shaft is provided at its smaller end with a tapering portion 14a which 60

ends in a cylindrical screw threaded portion 14^b; these portions 14^a and 14^b are made to correspond with the inside of the portions 10^a, 10^b of the liner. The shaft 14 is screwed into the head, thereby bringing the portion 14^a into frictional interengagement with the inside of the portion 10^a, and binding the shaft to the head with a combined screw joint and tapered push joint.

10 For a right handed golf club the threaded portions 8^a, 10^a, 12^a, and 14^b are all made left handed, so that the act of striking a ball with the club tends to tighten the joints; for a left handed club, these threaded portions would of course be right handed.

In practice, first a hole is drilled axially through the shank of the wooden head to the sole and is screw threaded for a certain distance at its lower end, and, thereafter, the upper part 20 of the socket may be tapered by means of a reamer, the tool is screwed into the liner 10 and both are then screwed home in the socket so that the smaller end of the liner projects from the sole 9 of the club, as shown in dotted lines in Fig. 5. The tool is then released from the liner and withdrawn. The portion of the liner projecting from the sole is now sheared off flush with the sole, and a nail 13 is driven through the liner into the wooden part of the head. 30 Finally, the shaft 14 is screwed home in the lined socket.

It will be evident that the shaft and head can easily be detached in order to permit various weights or sizes thereof to be tried before finally 35 selecting a club of the desired style and balance. The method of attachment is simple, and the parts are reduced to a minimum.

In the drawing the thicknesses of the wall of the liner and tubular shaft have been enlarged 40 somewhat out of proportion, for the sake of clearness.

By the term push joint I mean a joint formed by two parts—a receiving internally tapered part, and a corresponding insertable externally 45 tapered part, the taper being such that when the parts are pushed or forced one into the other they become frictionally wedged together. A unital taper of approximately .007 has been found satisfactory in practice.

50 I may of course provide other means for screwing the liner home in the socket, but the tool described above is found to be simple in construction and very handy in use.

The metal to metal joint between the shaft and head is very essential for a steel shafted club, while the persimmon or other wood head with a socket-liner as aforesaid, is not only strong, but has a neat appearance.

In practice it has been found that sometimes 60 the liner may be screwed too far into the socket, with the result that rather much of the screw threaded portion of the liner is cut away to render it flush with the sole of the golf club head. To obviate this I may provide gauge means on 65 the liner screwing home tool described above, and this means may conveniently take the form of a collar, sleeve or other stop, on the shank or handle, such as that shown in section at 15, Fig. 4; the stop shown comprises a tubular member 70 screwed into the handle of the tool. When the liner is screwed home to the correct amount in the socket, by means of the tool, this member abuts on the upper end of the shank of the head and prevents the liner being driven further 75 into the socket. The stop may be adjustable in

the handle so as to predetermine the amount by which the liner is screwed home, according to circumstances.

In order to ensure that the corresponding tapered parts of the socket, liner and shaft are 5 brought into interengagement before the limits of the screw threaded parts thereof are reached, plain cylindrical portions may be formed in a known manner on the socket, shaft or liner between the tapered and the threaded portions 10 thereof.

Instead of tapering the upper part of the socket in the wooden head as above described, the liner may be allowed to form the tapered portion there, as it is screwed into the socket. 15

While I have described my invention as applied to steel shafts, it is to be understood that it may just as well be applied to golf clubs having shafts made of any other metal suitable for 20 the purpose. In addition, the above described cylindrical screw threaded portions on the socket liner and shaft may instead be made to taper in the same direction as the tapered portions there- 25 of.

Binding cord or the like may be applied to the shank of the head and the lower part of the shaft in the usual manner.

I claim:

1. A wooden head for golf clubs provided with a 30 shank having a tapered socket therethrough, a tapered tubular metallic lining, screw threads at one end of said lining extending for a substantial distance in a direction lengthwise of the lining, said threads forming threads in the socket 35 wall at one end thereof to extend lengthwise of the socket for a distance corresponding to the position of the screw-threads in said lining, and a metallic shaft tapered at one end and telescoped into said lining, said shaft provided with screw 40 threads at said end which extend for a substantial distance in a direction lengthwise of the shaft, the threads on the shaft interiorly engaging the threads in the lining, the portion of the shaft above the threads and within the lining 45 contacting with said lining, whereby a metal to metal binding engagement will be established and maintained between the shaft and said lining throughout the entire length of that portion of the shaft which is telescoped into said lining, to 50 form a rigid joint between the shaft and head. 55

2. A wooden head for golf clubs provided with a shank having a tapered socket therethrough, a tapered tubular metallic lining, screw threads at one end of said lining extending for a substantial distance in a direction lengthwise of the lining and exteriorly engaging the wall of the socket to form threads at one end thereof to extend a substantial distance lengthwise of the socket corresponding to the position of the screw 60 threads in the lining, and a metallic shaft tapered at one end and telescoped into said lining, said shaft provided with screw threads at said end which extend for a substantial distance in a direction lengthwise of the shaft, the threads on the 65 shaft interiorly engaging the threads in the lining, the portion of the shaft above the threads and within the lining engaging said lining, whereby a metal to metal frictional surface engagement will be established and maintained between the shaft and said lining throughout the entire length of that portion of the shaft which is telescoped into said lining to form a rigid joint between the shaft and head, the said threaded 70 portions of the lining and shaft operating to draw 75

the shaft into the lining to effect a wedging engagement action between them.

3. A wooden head for golf clubs provided with a shank having a tapered socket therethrough, 5 a tapered tubular metallic lining, screw threads at one end of said lining extending for a substantial distance in a direction lengthwise of the lining and exteriorly engaging the wall of the socket at one end to form threads in the wall 10 extending a substantial distance lengthwise of the socket corresponding to the position of the screw threads in said lining, a metallic shaft tapered at one end and telescoped into said lining, said shaft provided with screw threads at said end 15 which extend for a substantial distance in a direction lengthwise of the shaft, the threads on the shaft interiorly engaging the threads in the lining, the portion of the shaft above the threads and within the lining engaging said lining, 20 whereby a metal to metal frictional surface engagement will be established and maintained between the shaft and said lining throughout the entire length of that portion of the shaft which is telescoped into said lining to form a rigid 25 joint between the shaft and head, and means securing the lining in the socket and against removal with the shaft from the wooden head.

4. A wooden head for golf clubs provided with a shank having a socket therethrough with a 30 substantially cylindrical portion and a substantially tapered portion, a tapering tubular metallic liner, the wall of the liner adjacent one end and for a substantial distance lengthwise of the liner being shaped to form external and internal 35 screw threads, the remaining portion of the liner above the threads being smooth both exteriorly and interiorly, the exterior threads of the liner engaging the socket wall at one end thereof to form threads in the socket extending for a substantial 40 distance lengthwise thereof, the remaining portion of the liner engaging the wall of the socket for the entire length of the socket, and a metallic shaft tapered at one end, said end of the shaft for a substantial distance lengthwise thereof 45 of being shaped to form screw threads adapted to engage the internal threads of the liner, the remaining portion of the shaft within the liner effecting surface interengagement with the liner to form a rigid joint, the said threads operating 50 to cause a wedging engagement action between the liner and shaft in a direction lengthwise of the shaft.

5. A golf club comprising a wooden head having a shank extending therefrom, said shank 55 having an internal bore therein comprising a plain tapering portion and a screw threaded cylindrical portion, a metallic liner having a plain tapering portion and a screw threaded cylindrical portion, the said screw threaded cylindrical portion having the screw threads formed 60 therein both interiorly and exteriorly thereof with the exterior portions of the said screw threads engaging the bore of said shank and with the plain tapering portion of said liner frictionally engaging said bore, and a metallic shaft connected 65 with said liner, said shaft having a plain tapering portion and a screw threaded cylindrical portion, with the screw threads of said cylindrical portion engaging the interior portions of the screw threads on said liner, and the plain tapering portion thereof frictionally engaging the plain tapering portion of said liner throughout the length thereof for supporting said wooden head in driving position.

said liner, and the plain tapering portion thereof frictionally engaging the plain tapering portion of said liner.

6. A golf club comprising a wooden head having a shank extending therefrom, said shank 5 having an internal bore therein comprising a plain tapering portion and a screw threaded cylindrical portion, a metallic liner having a plain tapering portion and a screw threaded cylindrical portion, the said screw threaded cylindrical portion having the screw threads formed 10 therein both interiorly and exteriorly thereof, with the exterior portions of the said screw threads engaging the screw threaded cylindrical portion of said shank and with the plain tapering portion of said liner frictionally engaging the plain tapering portion of said bore, and a tubular metallic shaft having a plain tapering portion and a screw threaded cylindrical portion, the screw threads on said tubular metallic 15 shaft engaging the interior screw threads on said liner and the plain tapering portion of said tubular metallic shaft engaging the plain tapering portion of said liner immediately above the screw threads therein for supporting said 20 wooden head in driving position.

7. A golf club comprising a wooden head having a shank extending therefrom, said shank having an internal bore therein, a metallic liner having a plain tapering portion and a screw 30 threaded cylindrical portion, the said screw threaded cylindrical portion having the screw threads formed 35 therein both interiorly and exteriorly thereof, with the exterior portions of the said screw threads engaging the bore of said shank and with the plain tapering portion of said liner frictionally engaging said bore, and a metallic shaft connected with said liner, said shaft having a plain tapering portion and a screw threaded cylindrical portion, with the screw threads of said cylindrical portion engaging the interior portions of the screw threads on 40 said liner, and the plain tapering portion thereof frictionally engaging the plain tapering portion of said liner for supporting said wooden 45 head in driving position.

8. A golf club comprising a wooden head having a shank extending therefrom, said shank having an internal bore therein, a metallic liner having a plain tapering portion and a screw threaded cylindrical portion, the plain tapering portion of said liner exceeding in length the length of said screw threaded cylindrical portion, the said screw threaded cylindrical portion having the screw threads formed 50 therein both interiorly and exteriorly thereof, with the exterior portions of the said screw threads engaging the bore of said shank and with the plain tapering portion of said liner frictionally engaging said bore, and a metallic shaft connected 55 with said liner, said shaft having a plain tapering portion and a screw threaded cylindrical portion, with the screw threads of said cylindrical portion engaging the interior portions of the screw threads on said liner, and the plain tapering portion thereof frictionally engaging the plain tapering portion of said liner throughout the length thereof for supporting said wooden 60 head in driving position.
